CLAIM

The ornamental design for a bottle cap, as shown and described..

DESCRIPTION

FIG. 1 is a perspective view of a bottle cap showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof; and,

FIG. 9 is another perspective view of the bottle cap of FIG. 1, shown in an open position.

The broken lines throughout the drawing figures depict portions of the bottle cap that form no part of the claimed design.
